CLAIM

The ornamental design for an exercising apparatus, as shown and described.

DESCRIPTION

FIG. 1 is a perspective view of an exercising apparatus showing my new design;

FIG. 2 is a front side view of the exercising apparatus shown in FIG. 1;

FIG. 3 is a bottom view of the exercising apparatus shown in FIG. 1;

FIG. 4 is a top view of the exercising apparatus shown in FIG. 1;

FIG. 5 is a right side view of the exercising apparatus shown in FIG. 1;

FIG. 6 is a left side view of the exercising apparatus shown in FIG. 1; and,

FIG. 7 is rear side view of the exercising apparatus shown in FIG. 1.
